UNITED STATES PATENT OFFICE.

DANIEL JONES, OF SWINDON, ENGLAND.

APPARATUS FOR TILTING BARRELS.

No. 801,320

Specification of Letters Patent.

Patented Oct. 10, 1905.

Application filed February 12, 1903. Serial No. 143,061.

To all whom it may concern:

Be it known that I, DANIEL JONES, a subject of the King of Great Britain, residing at the Union Hotel, Swindon, in the county of Wilts, England, have invented new and useful Improvements in Apparatus for Tilting Barrels, of which the following is a specification.

My invention relates to improvements in apparatus for tilting barrels. I attain these objects by the mechanism illustrated in the accompanying drawings, in which—

Figure 1 is a front elevation of the apparatus. Fig. 2 is a side elevation of the apparatus. Fig. 3 is a side view showing the apparatus in its position when in use.

This invention is constructed of two pieces of wood *a*, framed together at a short distance apart parallel to each other and fixed together by cross-pieces *b* with bolts *c* and nuts. At the top end of the frame I hinge a back plate *d* to one of the bolts. This said back plate *d* adjusts itself to any angle against a wall *2* or the like. At the bottom end of the frame I mount two small wheels *e*, which rest on the top of the barrel *1* near the bung-hole. Above the wheels *e* I mount an iron block *f*, pivoted on each side in suitable bearings *g*. The aforesaid block *f* is drilled through in order to receive a long screwed bolt *h* freely and nut *i*.

At the head of the bolt is a hole *j*, in which I insert a link *k* (or links) of a chain, which end link is connected to a metal catch, clip, or hook *l* for gripping the edge of the barrel *1*, as in Fig. 3.

On the screwed end of the bolt below the block above described is a nut *i* for adjusting the apparatus in order to tip the barrel *1* to any desired position, as in Fig. 3.

What I claim as my invention, and desire to secure by Letters Patent, is—

In an apparatus for tilting barrels, the combination of two pieces of wood framed together parallel to each other fixed rigidly by cross-pieces and bolts and nuts, having at its upper end a hinged plate, the two wheels journaled at its base, a block pivoted in the frame, a threaded bolt carrying an adjusting-nut and taking through said block, a hook connected by a link to an end of said bolt substantially as described.

In testimony whereof I have signed my name to this specification in the presence of two subscribing witnesses.

DANIEL JONES.
